INVALID LIFT

Orson P. Smith, Seattle, Wash.

Application October 23, 1951, Serial No. 252,670

5 Claims. (Cl. 5—86)

1

This invention relates to invalid handling mechanism of the character of, but having advantages and improvements over, the invalid lift of my United States Patent No. 2,494,591, issued on January 17, 1950; it being the principal object of this invention to provide an easily movable device, generally referred to as an invalid lift, whereby invalids, or others who are bed-ridden or immobilized by reason of injury, or while anesthetized, may be lifted from a bed, moved and lowered to a position for treatment, or of rest upon the same or upon another bed.

More specifically stated, the principal object of the present invention resides in the provision of an easily movable invalid lift, adapted to be rolled from and into various positions of use, and comprising a base housing adapted to be pushed beneath the usual hospital bed, and upon one side portion of which is a rotatably mounted standard which at its upper end mounts a cross-beam from the opposite ends of which, arms extend laterally and suspend a stretcher therefrom upon which the patient can be lifted from the bed, carried, turned, lowered into a chair or bath, or placed again upon the same or upon another bed.

It is a further object of the invention to provide means within the base structure of the device for winding in or paying out the cables to raise or lower the stretcher accordingly.

Yet another object of the invention is to provide an invalid lift of the above character which provides for the free rotation of the standard for the carrying of a patient as supported on the suspended stretcher, from a position over a bed from which he has been lifted to a position for being lowered onto an adjacent bed, and to equip the base structure of the lift with supports or legs that are laterally extendable therefrom to supportingly engage the floor so that the swinging of the patient to such position will not result in the tipping of the lift.

It is a further object of the invention to provide operating connections between the extendable legs and the rotatable standard whereby the legs will be caused to be automatically extended incident to that turning of the standard that disposes the suspended stretcher laterally of the base structure.

Other objects of the invention are found in the arrangement and manner of use of hydraulic jacks for the raising and lowering of the stretcher.

Still further objects of the invention reside in the details of construction of the various parts and in their relationship and mode of use, as will hereinafter be fully described.

2

In accomplishing these and other objects of the invention, I have provided the improved details of construction, the preferred forms of which are illustrated in the accompanying drawings, 5 wherein—

Fig. 1 is a perspective view of an invalid lift embodied by the present invention; a part of the standard being broken away to reduce the height of the view.

Fig. 2 is an enlarged horizontal section, taken on line 2—2 in Fig. 6 through the stretcher stabilizing post.

Fig. 3 is a vertical section, taken on line 3—3 in Fig. 2.

Fig. 4 is a horizontal section through the base portion of the lift, taken substantially on the line 4—4 in Fig. 6 and showing the cable system and hydraulic jacks.

Fig. 5 is a vertical section through the base portion of the lift, taken substantially on line 5—5 in Fig. 4.

Fig. 6 is a vertical section on line 6—6 in Fig. 4; parts being broken away for better illustration.

Fig. 7 is a horizontal section taken on the line 7—7 in Fig. 6.

Fig. 8 is a sectional detail in the vertical plane of line 8—8 in Fig. 4, showing one of the laterally extendable supporting legs in its retracted position.

Fig. 9 is a similar sectional view, showing the supporting leg in its extended position of support.

Fig. 10 is a diagrammatic illustration of the hydraulic central system for the control of the stretcher lifting jacks.

Referring more in detail to the drawings—

It is the intent that the present device shall be so designed and constructed that it can be easily rolled along the floor from room to room, or from one location to another in a room, and that it be of such size, and so limited in its weight that its use in present day hospitals by nurses is easily and readily accomplished.

In its present preferred form of construction 45 the lift comprises a box-like base frame or housing designated in its entirety by reference numeral 10. This housing is designed to contain the hydraulic jacks, and the controls therefor and the cable systems. It is rectangular in plan, as shown best in Fig. 4, and is so limited in its horizontal dimension and depth or height that it

can be easily rolled to position beneath the ordinary type of hospital bed. At its four corners, the base housing is equipped with caster wheels 50 55 11 of the character shown in Figs. 4 and 6, which

provide for the easy rolling of the lift in any direction merely by pushing it in that direction.

At one side of and centrally between its ends, a tubular standard 12 is supported on the housing 10 for axial rotation. To permit the standard to be so rotated, the lower end portion thereof is rotatably contained in vertically spaced bearing rings 13 and 14 that are fixedly secured in the frame structure of the base housing. The standard is supported in the bearings by means of an annular flange, or shoulder 15 that is formed about or fixed to the standard to engage flatly against the top surface of the bearing 13, as best shown in Fig. 6. When the lift is positioned adjacent a bed for its ordinary uses, the base structure 10 is disposed directly beneath the bed with the standard 12 closely adjacent a side edge thereof. It extends to a substantial distance above the level of the bed.

Rigidly fixed to the standard 12 at its upper end, is a horizontal cross-beam 16 in the form of a hollow housing. This beam normally extends equally toward opposite ends of the base structure and at its ends is equipped with hollow, integrally formed arms 17-17. These arms extend equally to the same side of the beam 16, as seen in Fig. 1. Upon rotating the standard 12, the cross-beam 16 and arms 17-17 can be swung from a position over the base 10, as seen in Fig. 1, to a directly oppositely extending position, or to any intermediate position. These arms 17-17 are of such length that the stretcher that is used in connection with the lift, and presently to be described in detail, when suspended from their outer ends can be disposed directly over or upon a bed beneath which the base structure 10 has been disposed.

The stretcher used in connection with the present lift, and designated in its entirety by numeral 20, can be of various forms but preferably comprises a rigid, metal frame structure of rectangular form, provided by parallel opposite side rails 20a-20a of tubular form, and cross rails 20b-20b that join the side rails across their opposite ends. Extended between the opposite side rails at regularly spaced and substantially close intervals, are flexible straps 21 for the support of a patient thereon. These straps are detachably secured at their ends to the rails to adapt them for use in a manner as described in my co-pending application filed under Serial No. 21,840 on April 19, 1948, now Patent No. 2,614,266, to provide for the easy placement on or removal of the patient from the stretcher.

Connected with the opposite side rails near each of the opposite ends of the stretcher, are suspending cables 25-25 which are attached to and diverge downwardly from the ends of lifting cables 26-26. Each of the cables 26 extends upwardly from its point of connection with the cables 25-25, and passes over a sheave wheel 28 mounted in the outer end portion of the corresponding arm 17, and from this sheave, it extends within and along the arm and about a sheave wheel 29 mounted within the corresponding outer end portion of the cross beam 16. From the sheaves 29-29, the cables 26-26 extend within the cross-beam 16 to the upper end of the tubular standard 12, and there pass over sheave wheels 30-30 mounted on the upper end of the standard as well shown in Fig. 6. From these latter sheave wheels, the cables 26-26 extend downwardly through the standard and from its lower end passing about sheaves 32-32 that are mounted in a yoke 33 carried on a cross-beam 34

that is fixed in the base housing 10 as seen in Fig. 6. From their respective sheaves 32 the cables extend forwardly along the cross-beam 34 and, respectively, about sheaves 35 and 35a that are mounted on the beam and then toward opposite ends of the base housing and after being wound about pulley systems, presently described, are attached at their ends respectively, to the ends of piston rods 40-40' of hydraulic jacks 41-41', as shown in Fig. 4.

Each of the pulley systems about which these cables are applied comprises a single sheave wheel 42 mounted in a yoke 43 at the end of the corresponding piston rod, and two sheaves 44 and 44' on a common axis 45 carried by a yoke 46 that is fixed to a rigid part of the base frame structure spaced from the sheave 42.

Each cable extends from its guide sheave 35 outwardly and passes about the sheave 44' of its pulley system, thence extends inwardly and about the corresponding sheave 42, thence outwardly and about the sheave 44, thence again inwardly and is secured at its end to a bracket 47 at the end of the piston rod 40. Thus with the retracting of the piston rods, the raising of the opposite end portions of the stretcher is accomplished. Furthermore, the arrangement provides for the raising and lowering of the stretcher to its full limits with relatively short movements of the piston rods.

The hydraulic jack cylinders 41-41' are arranged horizontally and in close parallel relationship lengthwise of the base housing as in Fig. 4, and are fixed against movement therein. Pressure medium as delivered to the opposite ends of the jack cylinders for the actuation of their pistons and piston rods is controlled by a system as shown in Fig. 10, wherein 50 designates a pump adapted to be driven by an electric motor 51, shown in Fig. 6 to be mounted in the base structure. Oil or other suitable fluid pressure medium is drawn to the pump from a storage tank 52, through a pipe 53, and is discharged from the pump through a pipe 55, cut-off valve 56, and pipe 57 to distributing lines 58-59 leading respectively to four-way valves 60 and 61. Each of these valves is connected by pipes 64 and 65 to the outer and inner ends of the respective jack cylinders 41-41'. Also the valves are connected by pipes 66-67 with a return line 68 to the storage tank 52. By manual manipulation of the valves 60 and 61, the pressure medium can be applied to the hydraulic cylinders as required to raise or lower the stretcher. Also, if desired to raise or lower one end of the stretcher with respect to the other end. The relative positions can then be held by closing the valves 60 and 61. Assuming that a patient has been placed on the stretcher and lifted from a bed while the stretcher is in a position over the base 10 as seen in Fig. 1, and it is desired then to turn the standard 20 so as to carry the patient to the opposite side of the standard for lowering onto a table or into another bed, the operator merely rotates the standard manually by pressure against one end of the cross-beam 16. To stabilize the stretcher during such turning, I have rigidly fixed downwardly extended posts 75 in each end of the cross-beam 16, and on the adjacent side rail 20a of the stretcher 20 have applied guides 76 through which the posts extend as shown in Fig. 1. Thus the stretcher is held against sway, and is caused to turn with the turning of the standard.

The guides 76 are closed at one side by pivoted

latch pieces 76' which may be swung out of holding position for the disconnection of the guides from the posts 75.

In order that the weight of the patient will not operate to tip the lift, upon swinging the stretcher to the position laterally of the base frame structure, I have equipped the base, at its opposite ends, with laterally extendable legs 80-80, shown in retracted position in Fig. 4. Each of these legs is supported for longitudinal guided travel between two lower rollers 81 and 82, and overlying rollers 83 and 84 as best shown in Fig. 9. Each leg is equipped at its outer end with a caster wheel 85.

When the stretcher is supported over the base housing 10, the legs 80-80 are retracted and are yieldingly retained in their retracted positions by the pull thereon of coiled springs 86 that have ends attached to the base frame structure, and their opposite ends attached to pull cables 86c that are attached to the legs. These springs as shown in Fig. 4, are arranged close to and in parallel relationship adjacent the outer side wall of the housing 10, and the cables extend therefrom over sheaves 87 to the corresponding legs and are attached thereto. However, when the standard is rotated to carry the stretcher and patient to the opposite side, laterally of the base, where support is required to prevent possible lateral tipping, the legs are automatically extended. This is accomplished by means of pull cables 90-90 attached to the legs at their inner ends and extended therealong to cable winding drums 91-91 mounted to turn on supporting shafts 92-92. Fixed upon and coaxially of the drums 91-91, are cable winding drums 93-93 of substantially smaller diameter, as shown in Figs. 4 and 5. Cables 95-95 are wound on the drums 93-93 and extended therefrom to the standard 12 and are fixed to lugs 96-96 on the opposite sides thereof. This cable arrangement is such that in rotating the standard toward one direction, or the other, the cables 95-95 are both drawn from the drums 93-93, thus rotating the drums 91-91 to which they are fixed, and causing the cables 90-90 to be wound in thereon and the legs 80-80 extended accordingly as has been shown in Fig. 9. With the rotating of the standard back to starting position, the coiled springs 86-86 return the legs to their retracted positions.

A feature of the leg design is disclosed in Figs. 8 and 9, wherein it is shown that each leg 80 has a downwardly and outwardly inclined portion 80x near its outer end. When this portion passes outwardly between the guide rollers 84 and 81 in the extending of the leg, the outer end of the leg is caused to move downwardly to thus contact the caster with the floor to give firm support. Likewise, when this part of the leg passes between the guide rollers with the retraction of the leg, it causes the leg 80 to be moved as to lift the caster from the floor.

The usual method of using the present device to move a patient, is to roll it to position with the base 10 below the bed and the arms 17-17 extended over the bed. The straps of the stretcher are then passed beneath the patient, and secured at their ends to the side rails of the stretcher. Then the lifting cables 26-26 are caused to be wound in by opening the valve 56 and valves 60 and 61 to deliver the pressure medium to the inner ends of the cylinders 41-41'. When the patient has thus been lifted, the valves can be closed to retain the stretcher in its lifted

position. If it is desired to lift one end of the stretcher above the other, the valves 60-61 are manipulated accordingly.

The lifted patient can be then transported to a place for treatment or rest, and lowered onto a bed or table. If necessary or convenient to do so, the patient can be swung to the other side of the base by the turning of the standard. If such is done, the legs 80-80 will be extended automatically to insure against tipping the machine. In its up and down movements the stretcher is guided and held against endwise or lateral sway by the guide posts 75 as contained in the guides 76.

15 The control valves 56, 60 and 61, and the switch which controls the flow of current to the electric motor 51 can be located at any convenient place on the base of the machine.

The present device provides for the easy and quick lifting of patients, and conveying them without injury. It also provides for the lifting of a patient for bedding change or for treatment that cannot be given while he is prone in bed. Handling of severely injured persons by this 20 means and in the way indicated is safely and most practically accomplished.

Having thus described my invention, what I claim as new therein, and desire to secure by Letters Patent, is:

30 1. An invalid lift of the character described comprising a caster mounted, supporting base structure having dimensions substantially equal to adapting it to be moved to and from a position beneath a bed, a vertical standard rotatably mounted on said base structure, medially of its ends and at one side thereof, and of a length to extend substantially above the bed beneath which the said base structure may be disposed, a cross-beam of substantially the length of the bed fixed to the upper end of the standard, having laterally directed arms at its opposite ends adapted to be disposed directly over the said base structure and bed and by rotative adjustment of the standard, to be swung from that position to 35 a position extending laterally of the supporting base and bed, cable winding means mounted in the base structure, cables extended from said winding mechanism, within said standard and cross-beam and downwardly from the arms of the latter, and a stretcher functionally suspended at its ends by the said cables from said arms, said winding mechanism being operable for the raising and lowering of the stretcher with a patient disposed thereon and to support the patient 40 on the stretcher for transportation.

2. An invalid lift as recited in claim 1 wherein supporting legs are slidably mounted in the opposite end portions of the said base structure, and adapted to be extended laterally therefrom at 45 that side thereof on which the said standard is rotatably mounted, and caster wheels at the outer ends of said legs, and means causing said legs to be adjusted automatically to cause the casters thereon to engage in supporting contact with a surface when the legs reach a fully extended 50 position.

3. An invalid lift as recited in claim 1 wherein supporting legs are slidably mounted in the opposite end portions of the said base structure, for extension and retraction at that side thereof on which the said standard is rotatably mounted, and means is operable by the rotative adjustment of the standard from a position at which the suspended stretcher is disposed over the bed, toward 55 a position laterally thereof, to cause the said legs

to be extended accordingly and to be engaged in supporting contact with the surface on which the lift is movable, said base structure having rollers therein for guiding the travel of said legs in their extending and retracting movements, and said legs having longitudinal portions thereof angularly offset and adapted to engage said rollers when the legs approach their limits of extension and cause the outer ends of the legs to be moved downwardly into contact with the supporting surface.

4. An invalid lift as recited in claim 1 wherein supporting legs are slidably mounted in the opposite end portions of the said base structure for extension and retraction at that side thereof on which the said standard is rotatably mounted, spring means attached to the said legs to actuate them from extended to retracted position, cable winding drums mounted in the base structure, and cables extending therefrom and to the standard and to the said legs whereby that turning of the standard that swings the stretcher to a position laterally of the base will cause turning of the drums and the said legs to be extended into supporting contact with a surface at that side of the base structure.

5. An invalid lift of the character described comprising a movable base structure of substantial horizontal dimensions and of limited height

- 5
10
15
- and adapted to be disposed beneath a bed, a standard rotatably mounted on said base structure at one side thereof, a cross-beam fixed to the standard at its upper end, and having arms at its opposite end portions extended laterally therefrom to positions over the base structure, a stretcher, and cables functionally suspending the stretcher from the ends of said arms of the cross-beam for the lifting and lowering of the stretcher onto the bed beneath which the said base structure may be disposed, said cross-beam being rotatable about the axis of the standard, downwardly extended guide rods fixed to the opposite end portions of the cross-beam, and guides on the stretcher slidably engaged with said rods to stabilize the stretcher in the rotary movements of the cross-beam and during travel of the lift.
